UNITED STATES PATENT OFFICE.

GEORGE STEWARD MACLEOD, OF SEATTLE, WASHINGTON.

STORM-SHIELD FOR VEHICLES.

1,094,665.

Specification of Letters Patent. Patented Apr. 28, 1914.

Application filed September 20, 1909. Serial No. 518,464.

To all whom it may concern:

Be it known that I, GEORGE S. MACLEOD, a subject of the King of Great Britain, residing at Seattle, in the county of King and 5 State of Washington, have invented a new and useful Storm-Shield for Vehicles, of which the following is a specification.

The invention relates to improvements in storm shields for vehicles.

10 The object of the present invention is to improve the construction of storm shields for vehicles, and to provide simple, inexpensive and efficient means for firmly securing the hinged glass front of a laundry or 15 other delivery wagon or analogous vehicle in position for shielding the driver, and capable of enabling the said front to be readily arranged overhead out of the way when desired.

20 With these and other objects in view, the invention consists in the construction and novel combination of parts hereinafter fully described, illustrated in the accompanying drawings, and pointed out in the claims 25 hereto appended; it being understood that various changes in the form, proportion, size and minor details of construction, within the scope of the claims, may be resorted to without departing from the spirit or sacrificing any of the advantages of the invention.

In the drawings:—Figure 1 is a side elevation partly in section of a portion of a delivery wagon having a storm shield, provided with locking means, constructed in accordance with this invention. Fig. 2 is a transverse sectional view. Fig. 3 is an enlarged detail sectional view, illustrating the manner of supporting the storm shield overhead out of the way. Fig. 4 is an enlarged view of a portion of the storm shield, showing one of the locking devices. Fig. 5 is a vertical sectional view of the same. Fig. 6 is a vertical sectional view, taken substantially on the line 6—6 of Fig. 5. Fig. 7 is a horizontal sectional view on the line 7—7 of Fig. 6. Fig. 8 is a detail perspective view of the slidable latch, equipped with a single lift. Fig. 9 is a detail view of a slidable latch, provided with opposite lifts. Fig. 10 is a detail view, showing a lower keeper plate for use on dash boards not equipped with rails.

55 Like numerals of reference designate corresponding parts in all the figures of the drawings.

In the embodiment of the invention illustrated in the accompanying drawings, the storm guard consists of a glass front 1, hung from the top 2 of a delivery wagon 3 at a 60 point above the dash board 4 by hinges 5, and adapted to protect the driver from dust, rain and the like. The glass front consists of a plate of glass and a frame of wood, or other suitable material, but the locking device herein shown may be applied to any 65 form of hinged storm doors.

The hinged front 1 is equipped at opposite sides with slidable latch plates 6, projecting below the lower edge of the hinged front and adapted to engage the rail 7 of the dash board 4. The latch plate 6 is provided with upper and lower longitudinal slots 8 and is secured to the hinged front by screws 9, extending through the slots 8 70 and embedded in the frame of the hinged front. The latch plate is actuated by a coiled spring 10, arranged within a casing 11 and engaging a lug or flange 12, extending from the inner face of the latch plate 80 and slidable within the casing 11, as clearly illustrated in Figs. 6 and 7 of the drawings. The casing, which is let into the frame, is open at the front and is approximately semi-cylindrical, being provided with side flanges 13 and terminal ears 14, which are arranged in flush relation with the edge of the side bar of the frame of the hinged front. The ears 14 are pierced by suitable fastening devices for securing the casing to the frame of the hinged front, and the screws 9 also pierce the ears, as clearly illustrated in Fig. 6 of the drawings. The screws guide the latch plate in its sliding movement, and the coiled spring 10 is interposed between the upper end wall of the casing 11 and the lug or flange 12. The lug or flange 12 is provided with a shank 15, which is secured in an opening of the slidable latch plate by heading the said 95 shank at the outer face of the latch plate, as shown in Fig. 6.

The lower end of the slidable latch plate 6 has an inclined edge 16 and is provided at the lower end thereof with an off-set hook-shaped portion 17, having a recess 18 located at the lower end of the inclined edge 16, as clearly shown in Fig. 5 of the drawings. When the hinged front is swung downwardly and forwardly, the hinged edges of the side latches are carried into engagement with the rail 7 of the dash board 105 110

and the latches are thereby lifted and are automatically engaged with the dash board rail. The springs maintain the latches firmly and securely in engagement with the dash of the vehicle. The latches are made right and left hand, and each is provided with a lift 19, preferably consisting of a curved outwardly extending flange adapted to enable the latch to be readily raised by the operator. The latch, however, may be equipped with oppositely extending lifts 20, as illustrated in Fig. 9 of the drawings, and when the device is applied to a dash board not equipped with a rail, a lower keeper 21 is used. The keeper 21 consists of a plate secured to the dash board 22 near the upper edge thereof and projecting above the same and having a rounded upper edge or bead 23 for engaging with the slidable latch.

20 The vehicle is provided at opposite sides of the top with interiorly arranged upper keepers 24, consisting of attaching portions 25 and inclined engaging portions 26. The engaging portion 26 extends upwardly and forwardly toward the front of the vehicle and its upper end is spaced from the inside of the top, and when the hinged front is swung upwardly the hook-shaped projecting portion of the latch is carried into engagement with the front inclined face of the keeper, and the latch is forced backwardly against the action of the spring, which carries the hook-shaped projection into engagement with the upper edge of the inclined portion 26, as soon as the said hook-shaped projection is lifted above the keeper. The spring maintains the latch in engagement with the upper keeper and securely holds the storm front in an elevated position. The upper keeper may consist of either a casting or a piece of malleable metal, provided with an intermediate quarter bend to arrange its inclined portion transversely of the vehicle.

Having thus fully described my invention, what I claim as new and desire to secure by 45 Letters Patent, is:—

1. A latch designed to be mounted on a swinging member and comprising a casing open at the front, a spring housed within the casing, a latch plate slidable over and covering the open front of the casing and provided with slots and having a lug extending into the casing and engaged by the said spring, said latch plate being provided at one end with an inclined edge and having an 50 offset hook-shaped engaging portion located at one end of the inclined edge, an arm extending from one of the side edges of the latch plate and forming a lift, and fastening devices extending through the slots of the 55 latch plate and permitting a limited sliding movement of the same.

2. A latch designed to be mounted on a swinging member and comprising a casing open at the front, a spring housed within the 60 casing, a latch plate slidable over and covering the open front of the casing and provided with slots, said latch plate having an inclined outer edge and provided at one side thereof with an offset hook-shaped engaging 65 portion, fastening devices extending through the slots of the latch plate and permitting a limited sliding movement of the same, and a coacting keeper consisting of an attaching portion and an inclined engaging portion extending upwardly from the attaching portion and presenting an inclined face and having an upper engaging edge adapted to 70 extend into the hook of the latch plate.

In testimony, that I claim the foregoing 75 as my own, I have hereto affixed my signature in the presence of two witnesses.

GEORGE STEWARD MACLEOD.
